UNITED STATES PATENT OFFICE.

WILLIAM O. BISBEE, OF CAMDEN, NEW JERSEY.

MACHINE FOR SPLITTING FIRE-WOOD.

Specification of Letters Patent No. 13,485, dated August 28, 1855.

To all whom it may concern:

Be it known that I, WILLIAM O. BISBEE, of the city of Camden and State of New Jersey, have invented a new and Improved Apparatus for Rifting Fire-Wood; and I do hereby declare that the following is a full, clear, and exact description of the same, reference being had to the accompanying drawing, making a part of this specification, 10 in which—

Figure 1 is a sectional elevation of my improved apparatus; Fig. 2, a cross section of the same on the line 1, 2. Fig. 3 is a ground plan, and Fig. 4 a ground plan with 15 the slide and box removed.

The same letters of reference allude to similar parts throughout the several views.

My invention consists in placing the block of wood to be operated upon, within a box 20 attached to a stationary frame, on which a sliding frame with a knife is caused to have a backward and forward movement by cranks and rods, or any other convenient driving apparatus, so that the said knife 25 may, on the forward motion of the sliding frame, so operate upon the block of wood as to rift therefrom a flat piece. This, after being entirely separated from the block, drops down into such a position, that the 30 sliding frame on its backward or reverse movement draws the said flat piece against a series of knives with vertical cutting edges secured to the stationary frame and arranged in a peculiar manner as hereinafter 35 more fully described, so that the flat piece of wood may be again rifted into a number of strips suitable in size for kindling fires and other similar purposes; the same process being continued until the entire block has 40 been rifted when another may be placed within the box to be operated upon in a similar manner.

To enable others skilled in the art to make and use my invention, I will now proceed to 45 describe its construction and operation.

A is the stationary frame of the machine; B, the sliding frame which fits in V shaped guides *a* on the frame A, and has a reciprocating motion given to it by the crank J, the 50 pin I of which is embraced by one end of the connecting rod H, the other end being connected to lugs on the sliding frame P. On the crank shaft is the spur wheel K gearing into the driving pinion L on the 55 shaft M, which is caused to revolve by any convenient means. On the sliding frame B

is secured the first rifting knife C which is arranged so that, when moved forward to its farthest extent, its edge may enter a small recess *d* on the back of the stationary 60 box D, the latter having lugs *f* for securing it to the guides *a* of the frame A. The sliding frame B passes underneath the box D and has a shoulder at *x*.

G are vertical edged knives, secured to 65 the frame A, and arranged in the peculiar manner shown in Fig. 4 for a purpose hereafter set forth.

N is the block of wood to be operated upon, placed within the box D and resting 70 on the sliding frame B. Directly under this block, under the sliding frame, and hinged to the frame A is the trap E of about the same width as the inside of the box D. To keep this trap pressed against B when not 75 otherwise depressed, is the spring F and the lip *e* on the frame A prevents it from being depressed too far.

Operation:—The block of wood N being placed within the box D, and the working 80 parts of the machine being in the position shown in the drawing, on turning the crank J the sliding frame B and with it the knife C is moved forward until the edge of the latter enters the notch *d*, completely rifting 85 a flat piece from the block N. It will be observed however that as the knife is penetrating the wood, the piece about being rifted therefrom will on account of the inclined edge of the knife have a tendency to bend 90 downward. The spring trap E accommodates itself to this bending of the piece until it is entirely rifted from the block when by the reaction of the spring the trap returns to its former position. The flat piece 95 of wood has now fallen onto the trap and the sliding frame B receded so far as to be entirely free from the said piece, which on the return motion of the sliding frame, consequent upon the further turning of the 100 crank, is caught by the shoulder *x* and forced along over the spring trap, and under the first rifting knife C toward and against the vertical edged knives G. Now if the cutting edges of these knives were in a line 105 with each other it would be impossible to rift the flat piece, (already cut from the block) into strips as the latter would in that case become wedged, breaking either the blades or the machine. I therefore arrange my vertical knives as shown in Fig. 110 4, that is with the edges of some in advance

of those of the others and their sides set at different angles, so that the flat piece on being forced against their edges by the shoulder α may be cut into strips, which 5 will pass between the blades and be guided by the angle of their sides, thus spreading themselves out and falling (on the further movement of the machine) through the space within the frame A. The machine has 10 now returned to its former position the block N having dropped down consequent upon the removal of the flat piece rifted therefrom, and the operation may be continued until the entire block is consumed, 15 when another may be placed within the box.

Having now described the nature of my

invention I wish it to be understood that I do not wish to confine myself to the exact form of the frame or method of operating the machine or to the exact number of vertical knives shown. But 20

What I claim and desire to secure by Letters Patent is—

I claim the vertical knives G as arranged with their edges a distance in advance of 25 each other and their sides at different angles so as to act effectually as a means of rifting wood.

WILLIAM O. BISBEE.
